CLAIM

The ornamental design for a bottle, as shown and described.

DESCRIPTION

FIG. 1 is a bottom perspective view showing a first embodiment of our new design of a bottle;

FIG. 2 is a top perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof;

FIG. 9 is a bottom perspective view showing a second embodiment of our new design of a bottle;

FIG. 10 is a top perspective view thereof;

FIG. 11 is a front elevation view thereof;

FIG. 12 is a rear elevation view thereof;

FIG. 13 is a right side elevation view thereof;

FIG. 14 is a left side elevation view thereof;

FIG. 15 is a top plan view thereof; and,

FIG. 16 is a bottom plan view thereof.

(Continued)

The broken lines in the drawings depict portions of the bottle that form no part of the claimed design.
